US0D1062528S

(12) **United States Design Patent** (10) **Patent No.:** **US D1,062,528 S**
(45) **Date of Patent:** **** Feb. 18, 2025**

(54) **AERIAL VEHICLE**

(71) **Applicant:** **Fujian Huoshi Network Technology CO., LTD**, Xiamen (CN)

(72) **Inventor:** **Jianjia Zhao**, Zhangzhou (CN)

(73) **Assignee:** **Fujian Huoshi Network Technology CO., LTD**, Xiamen (CN)

(**) **Term:** **15 Years**

(21) **Appl. No.:** **29/913,212**

(22) **Filed:** **Sep. 28, 2023**

(51) **LOC (15) Cl.** **12-06**

(52) **U.S. Cl.**

(57) **CLAIM**

The ornamental design for an aerial vehicle as shown and described.

DESCRIPTION

FIG. 1 is a perspective view of an aerial vehicle, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The dash-dash broken lines in the drawings depict portions of the aerial vehicle that form no part of the claimed design. The dot-dash broken lines in the drawings denote the boundaries of the enlarged detail view and form no part of the claimed design.

1 Claim, 9 Drawing Sheets
